UNITED STATES PATENT OFFICE.

MILON J. TRUMBLE, OF LOS ANGELES, CALIFORNIA, ASSIGNOR, BY MESNE ASSIGNMENTS, TO SIMPLEX REFINING COMPANY, A CORPORATION OF CALIFORNIA.

APPARATUS FOR TREATING PETROLEUM.

1,260,598.

Specification of Letters Patent. Patented Mar. 26, 1918.

Continuation in part of application Serial No. 586,382, filed October 10, 1910. This application filed February 17, 1916. Serial No. 78,988.

To all whom it may concern:

Be it known that I, MILON J. TRUMBLE, a citizen of the United States, residing at Los Angeles, in the county of Los Angeles and State of California, have invented a new and useful Apparatus for Treating Petroleum, of which the following is a specification.

This invention relates to an apparatus suited for use in a process for the treatment of hydrocarbon oils or petroleum to separate the lighter or more volatile constituents therefrom, the process being particularly intended for so treating the crude oil as to remove and save the gasoline and other light volatile products.

On October 10, 1910, I filed an application for Letters Patent on a process for treating petroleum, Serial No. 586,382, of which this application is a continuation as to all matters in common.

The main object of the invention is to provide an apparatus whereby the above described vaporization or separation may be effected in the most rapid, economical and efficient manner.

Another object of the invention is to provide an apparatus of extremely limited size compared to the apparatus generally used for such purposes.

The process consists essentially in heating the oil in a closed receptacle to a temperature above the boiling point of the lighter constituents of the oil for the pressure at which they are to be vaporized, the oil being maintained while it is being heated at such pressure as to prevent vaporization during the heating operation, then allowing the heated oil to pass into a vaporizing chamber where the lighter constituents of the oil immediately expand and pass into state of vapor or gas by reason of the temperature thereof being higher than the boiling point for the pressure in said vaporizing chamber, and withdrawing said vaporized or gasified products from the vaporizing chamber. The process further comprises in the vaporizing operation exposure of the oil in a thin film or layer to the action of a heated surface, thereby expediting the separation of the volatile constituents from the heavier constituents and withdrawing the vaporized constituents as fast as they are released from such film or layer.

Other objects and advantages of the process will appear hereinafter.

The accompanying drawings illustrate an apparatus or vaporizer suitable for carrying out the invention, and referring thereto:—

Figure 1 is a vertical section of a vaporizer showing the form thereof which I consider best adapted for carrying out the process.

Fig. 2 is a section on the line x^2-x^2 of Fig. 1, looking in the direction of the arrows.

Referring to Fig. 1, the apparatus comprises a furnace or heating chamber 1 provided with a fire box or combustion chamber 2 for generating heat therein and with a stack or chimney 3. In said heating chamber is provided a heating coil 4, said coil being of sufficient length and capacity to retain the body of oil therein for a considerable time in heat absorbing relation with the heating chamber. This coil 4 is supplied with oil at one end thereof by a supply pipe 5 having an inlet valve 6, said supply pipe communicating with regenerating means for heating the oil as it is supplied to the coil by means of heat absorbed from the out-going products of the process. At the end of the coil 4 which is farthest from the inlet pipe 5, a drainage pipe 8 is provided having a draw-off cock 9, the coil 4 inclining continuously from the inlet end to the said farther end, so that any water separated from the oil while in said coil collects at said drainage pipe and may be drawn off from time to time. A pipe 10 extends upwardly from the coil near the end which is farthest from the inlet end of the coil, said pipe extending to the top of one of a series of vaporizing chambers 11 which are located within the stack 3, so that the walls of said cylinder are heated by the hot gases passing upwardly through said

stack. A valve 12 is provided in said pipe 10 to hold the oil under pressure in coil 4 and to control the supply of oil to the chamber 11, said valve having an operating handle 13. From the lower end of the lower vaporizing chamber 11 extends a drainage pipe 15 for residual oil, said drainage pipe having an outlet valve 16 which is adjusted in position to maintain a body of oil in the drainage pipe 15 and in the lower part of the vaporizing chamber 11 as shown in Fig. 1, so as to form a liquid seal at the bottom of said chamber and prevent outflow of vapor therefrom, except through the vapor outlets and vapor line, as hereinafter set forth. For showing the level of the oil in the vaporizing chamber pet-cocks 17' may be provided on a vertical pipe 17 connected near its upper and lower ends by pipes 18 to the lower vaporizing chamber 11.

The vaporizing chambers 11 each consist of a rectangular box or casing having inclined walls 46 on which the oil descends in a thin layer from a spreader plate 47 each of which preferably consists of an angle iron member extending across the chamber 11. The vaporizing chambers 11 are connected by pipes 48 and 49, and vapor outlets 50 are provided in the upper chamber 11, similar outlets 51 being provided for the lowest chamber 11, no vapor outlets being used in the middle chamber 11. The outlets 50 connect directly into a vapor line 20, and the outlets 51 may be connected directly into the line 20 through a valve 52, or this valve may be closed and the outlets 50 may be connected through a valve 54 with a primary distillate pipe 53. When the valve 54 is closed, which is the normal operating condition, the vapor passes through the vapor line 20. The vapor line 20 leads through condensing means which also form part of the regenerative system for supplying heat to the incoming oil, said line 20 extending through a jacket tube 28 the oil being supplied under pressure at one end of said tube by a pipe 29 into which the oil is pumped by a pump 30, the other end of said jacket tube 28 being connected by a pipe 31 to one end of a tube 32 surrounding the residual outlet pipe 15, the farther end of said jacket tube 32 being connected to the oil supply pipe 5 for the heating coil 4. Valves 34, 35 may be provided respectively in the vapor line and in the delivery line for the condensate.

The process is carried out as follows in the above described apparatus: The valve 12 is partially closed and oil is pumped in at the pressure required in the heating operation, say, three or more pounds per square inch according to the required temperature and is maintained through the regulation of

such valve 12. The oil in entering passes in through pipe 29, through jacket 28, pipe 65 31, jacket 32 and pipe 5 to heating coil 4, said heating coil being of sufficient length and area to enable the heating or furnace chamber 1 to supply the required amount of heat to said coil in the continuous passage 70 of the oil from one end of the coil to the other to vaporize the product desired to be taken off. The said oil has a slow movement and a continual increase of temperature from the inlet to the delivery point. 75 In this heating of the oil a portion of the water is released or separated therefrom, if such is held in suspension in the oil, and tends to settle in the lower end of the coil, being drawn off when required through the 80 valve 9. The heated oil passes upwardly through pipe 10 and valve 12 and in passing into the vaporizing chambers 11 is subject to a sudden expansion by reason of the lower pressure in said chambers and in this expansion the lighter constituents of the oil, namely, gasolene, kerosene, etc., are suddenly passed into the form of vapor gas. The oil entering each of the vaporizing chambers 11 is spread in a thin film over 90 the plates 46 forming the heated walls of the chambers 11, and the heat supplied through said walls maintains a temperature sufficient to cause such lighter products to be boiled or evaporated from the oil, and 95 the oil is maintained in a thin layer or film on said walls, so as to present maximum surface for evaporation and facilitate the immediate release of the vapor or gas from the liquid. As fast as such vapor or 100 gas is formed it is withdrawn or passes out through the outlet pipes 50 and 51 and vapor line 20. The process may be carried out in any apparatus adapted to provide for heating of the oil under pressure and then subjecting it to sudden expansion on lowering the pressure, so as to cause sudden release of the lighter products therefrom in the state of gas or vapor.

Under ordinary conditions all the vapor 110 is mixed together and carried away through the pipe 20, being suitably condensed to form a commercial product. Under such conditions the valve 54 is closed, and the valve 52 is open. If desired the valve 54 115 may be opened and the valve 52 closed, the lighter distillates taken off through the outlets 50 being delivered to the primary distillate pipe 53, the heavier distillates taken off through the outlets 51 being taken off 120 through the pipe 20 as already explained.

I claim as my invention:—

1. In an oil refining system, a vaporizing chamber having its lower outer wall inclined; a feed pipe delivering oil to said 125 chamber at or near the upper end of said

inclined wall; means for spreading the oil so delivered over said inclined wall; a vapor outlet pipe communicating with the interior of said chamber; and a residuum pipe connecting with the lower part of said chamber.

2. A vaporizing chamber as set forth in

claim 1 in which the means for spreading the oil comprises a spreader plate extending across the chamber.

10

In testimony whereof, I have hereunto set my hand at Los Angeles, California, this 10th day of February, 1916.

MILON J. TRUMBLE.
